SYRINGE

Oscar O. R. Schwidetzky, Hasbrouck Heights,
N. J., assignor to Becton Dickinson & Co.,
Rutherford, N. J., a corporation of New Jersey

Application November 26, 1932, Serial No. 644,432

11 Claims. (Cl. 128—231)

The invention relates to syringes of the type which comprises a compressible air bulb and a cylinder or barrel for receiving fluids, the bulb being associated with the barrel by frictional contact with an extension of the bulb. Such syringes usually comprise a glass barrel whose capacity is materially in excess of that of the air space within the bulb while the air channel or channels through which communication is established between the barrel and the bulb are of such limited dimensions as to prevent the liquid within the barrel from flowing into the bulb when the barrel is held with the nozzle pointing upward. Syringes of this character are and have been in wide use for many years but they have certain defects, for example, that the bulbs cannot be satisfactorily flushed, cleaned, and drained, which have thus far not been satisfactorily remedied. It is the object of the present invention to remedy such defects and to improve the syringe structurally.

In existing bulbs, due to their structural character, the interior of the bulbs can be drained only by admitting fluid into and ejecting fluid out of the relatively small air passage which extends through the neck of the bulb and which is purposely kept small for the reason above stated. Attempts at flushing, cleaning, and draining of the bulbs through this small channel have never been satisfactory. In studying the cause I have found that in the vulcanization process employed in the manufacture of the bulbs the interior surface of the neck portion of the bulb is not smooth or even but is usually full of crevices within which undesirable fluids and solids are capable of lodging without being ejectable therefrom by the flushing or draining operation. Fine powder appearing on the interior of the bulb as a result of the vulcanizing process settles in the crevices referred to and as it cannot well be flushed out, in time finds its way into the medicinal liquids contained in the barrel and introduces an undesirable impurity. Perfect flushing could, of course, be attained by greatly enlarging the air channel but this in turn would defeat the principle of the syringe that the air channel must be kept so small that when the syringe is held barrel up or when laid on a flat surface, fluid will not flow into the bulb through the channel. I have found that the unsatisfactory conditions referred to can be completely remedied by establishing a relatively large drainage passage or passages through the sides of the neck of the bulb in the region of the inner wall of the forward part of said neck and having the neck of sufficient length that when as-

sociated with the barrel the large openings of the large passages will lie between two portions of the neck which are in continuous frictional engagement with the inner wall of the barrel above and below the said openings. In this way when the barrel and the bulb are assembled there will be established, notwithstanding the presence of the large lateral passages of the neck, a fluid- and air-tight connection between the neck and the barrel which will persist even though the bulb is completely compressed and which will, in the ordinary use of the appliance, be wholly unaffected by the presence of these large openings. In the use of the syringe all of the air used for drawing in or expelling fluid into or from the barrel passes wholly through the small channel. When, however, the bulb is detached from the barrel and flushed, the flushing fluid rushes in through the large lateral channels, practically none of it entering through the small channel, and the forces developed in the flushing operation unseat all impurities since the liquid in rushing in the larger channels directly reaches all of the crevices and irregularities of that part of the interior of the bulb where those irregularities usually appear. When the flushing liquid is ejected from the bulb it flows out practically entirely through the large passages and sweeps away all impurities contained in the interior of the bulb and then as the bulb finally drains, allows everything which was inside of the bulb to be drained away. If, for example, a certain medicament was used in the syringe for one purpose and a part of it had slipped into the interior of the bulb through the small aperture and the syringe was next to be used with an entirely different medicament, it is possible with the new arrangement to thoroughly remove all traces of the first medicament from the interior of the bulb before the syringe is reassembled for the use of the second medicament. There is no chance of any intermixture as between remnants of the first medicament and the second medicament.

In order to strengthen the neck of the bulb and also to enable me to reduce the size of the smaller passage and yet preserve a reliable functioning thereof, I provide a metal tube to constitute the smaller passage and preferably so locate the inner end of said tube that it will lie approximately flush with the side of the larger channels, in this way assuring complete drainage when the bulb is flushed and preventing the collection of a liquid accumulation around the inner end of the metal tube.

The invention is illustrated in the accompany-

ing drawing in which Fig. 1 is a plan view partly broken away of the improved syringe. Fig. 2 is a section taken on line 2—2 of Fig. 1, Fig. 3 is an enlarged view partly broken away and in section 5 showing a side view of the bulb of Fig. 1. Fig. 4 is a view similar to Fig. 3, the sectional portions thereof being transverse to those of Fig. 3. Fig. 5 is a sectional view on line 5—5 of Fig. 4.

In the drawing A is a glass barrel of conventional type having a fluid inlet at C, and bulb- and bulb-neck-engaging portions D. B is a rubber bulb, the air space in which is preferably less than the liquid space in the barrel A. The bulb is associated with an integral neck N having a forward section N', said section N' being preferably thicker than the walls of the bulb itself and the walls of the neck N. This thickening of the section N' results in increased resistance to transverse compression and therefore participates in insuring a liquid-tight fit between the exterior of the section N' and the wall of the glass barrel with which it is in compressing contact around its entire periphery.

At the rear of N' are situated the usual surface irregularities, crevices, and pockets indicated at E. Relatively large channels F are provided laterally through the walls of the neck N and extend to the region occupied by the irregularities E. There may be one or more of such passages F. I preferably use two, extending each angularly toward the longitudinal axial center line of the bulb and neck and forming each an obtuse angle with reference to the lines drawn centrally through the apertures F and the longitudinal axial line drawn from the center of the bulb toward the neck. A rigid tube T, preferably of corrosion-resistant material or surfaced with such material, of small or minute calibre, is forced through an opening adapted to receive such a tube in the neck section N', being positioned in and extending through the end wall N' of the neck into the interior of the bulb and being held in place by frictional engagement with the walls of the aperture in the end wall N' through which the tube T extends. The tube T may be angularly or otherwise inserted and be located anywhere with respect to the face of the wall N', at the periphery, at the center, or any other place. As illustrated the tube T extends 50 into communication with one of the large channels F (Fig. 3), terminating practically flush with the wall F' of the channels F; F' being the wall of the passage F nearest the interior of the barrel. The minute or reduced character of the small aperture through the tube T is illustrated in Fig. 2 from which it will be apparent that the aperture is so minute as to reduce to a minimum the possibility of leakage of fluid into the bulb through such passage under any conditions of use. The preferred dimensions of the diameter or diameters of the passage or passages which establish communication between the interior of the air bulb B and the barrel A are such as to represent minimum requirements with respect to the proper expulsion of air from the bulb through the passage or passages into the syringe barrel. The selection of these minimum dimensions cooperate with the other parts of the structure to prevent entry of the fluid from the barrel into the interior of the bulb when the syringe is held bulb down. If these passages of the stated minimum diameters have rubber walls as has thus far been the practice, the passages become reduced in size when the neck of the bulb is forced into the larger end D of the syringe

barrel. This in turn reduces the passages to less than minimum and brings about a condition where the syringe does not function as perfectly as it should. By using rigid tubes T to define the passages, the minimum condition described will be defined by the passages through the tubes T which, having rigid walls, will not be compressed or altered by reason of compression of the rubber portions of the neck as the neck is inserted in the barrel. One object of the metal tubes T, therefore, is to maintain a fixed diameter of the air passages through which communication is established between the air of the bulb and the barrel of the syringe which in turn makes it possible, after adopting the preferred minimum diameter of the passage through T to maintain that diameter in all future manipulations of the syringe or its parts.

The neck N inclusive of its section N' is of such length that when assembled with the barrel A as shown in Fig. 1, there will be a continuous frictional engagement between the entire exterior surface N² of the neck section N' and the inner wall of the barrel A forward of the large apertures F and that there will also be a continuous frictional engagement between the entire exterior surface N³ of the neck section N' and the inner wall of the barrel A rearward of the large apertures F. In this way, when the bulb and barrel are assembled the large apertures F are completely sealed against access therethrough of liquid or passage therethrough of air, said sealed condition persisting throughout the use of the syringe even when the bulb is fully compressed in line with the apertures F.

The tube T may be located in any other position than that shown provided its interior orifice is in communication with the air contained in the bulb, but it is preferred to locate the tube T at the point shown for the reasons explained.

There may be several tubes T provided their aggregate transverse area is sufficiently small to prevent material leakage into the bulb when the syringe containing fluid is held nozzle up. It will be apparent from the foregoing description that

the syringe of Fig. 1 will function in such a way that the large passage F may be regarded as sealed. Should liquid from the barrel A be accidentally drawn into the bulb B, as for example

when the syringe is held bulb down and the bulb is then compressed and the pressure released, all such liquid is ejectable from the interior of the bulb notwithstanding the presence of the pockets and irregularities E by merely inverting the syringe and compressing the bulb, since all such liquid will on such inversion, collect in the passages

from which the liquid will find outlet and drainage through the tube T.

When the bulb is detached from the barrel the large passage F ceases to be sealed and the bulb can be thoroughly, completely, and reliably flushed out and drained through those passages F. These passages F being large with respect to the tube T, the flushing or cleaning liquid will practically all enter through the passages F and

will flush and drain out through the passages F, any liquid which might accumulate in T being readily forced out by closing the passages F with the fingers and pressing the bulb.

It will be observed in Fig. 3 that the exterior of the neck N at the portion N² is slightly tapered. This feature enables the neck to be very readily inserted in the neck-receiving end of the barrel

A. The taper is so slight, however, as not to interfere with the effectuating of a close fit between

the fingers and the neck N. The exterior of the neck N at the portion N³ is also slightly tapered. This feature enables the neck to be very readily inserted in the neck-receiving end of the barrel A. The taper is so slight, however, as not to interfere with the effectuating of a close fit between

the wider portions of the sections N² and the inner wall of the barrel forward of the large apertures F. The degree of compression of the neck sections N² and N³, when inserted in the barrel 5 and making a continuous circumferential frictional contact with the inner wall of the barrel is usually such as to give a slightly oval configuration to the large apertures F in a direction longitudinal of the barrel as indicated in Fig. 1. The 10 oval configuration of the apertures with the major axes of the ovals extending in a direction longitudinally of the barrel, is an indication of the fact that the proper compression on the neck of the bulb within the barrel has been achieved 15 and also that the wall thicknesses of the neck portion of the bulb are properly dimensioned to prevent longitudinal compression of the neck and incidentally thereby preventing creases or wrinkles from forming in the sections N² and N³ and 20 rendering impossible the passage of air or liquid between the outer walls of these sections and the inner wall of the barrel such as would be the case if the walls were so insufficiently compressed transversely or so thin as to prevent the orifices 25 of the apertures F to retain their round form or to become oval transversely of the barrel when the neck is inserted in the barrel. In some cases it may be desirable to use rigid tubular elements, 30 of material similar to that used for the tubes T, to line the large apertures F, in which case the said tubular reinforcing members should be so associated with the neck of the bulb as not to interfere with the cross-wise compressibility of the bulb or the sealing effect of the parts N² and 35 N³ of the bulb when the bulb is in place as shown in Fig. 1 of the drawings.

It is apparent that numerous modifications may be made without departing from the scope of the invention as covered by the appended claims 40 whose purpose it is to include and embrace any such modifications or equivalents.

I claim:

1. A syringe comprising a barrel provided at one end with a nozzle and at its opposite end 45 with an inner surface adapted to frictionally engage the neck of a bulb, a compressible bulb having an end wall and a neck adapted exteriorly thereof to frictionally engage said inner surface of said barrel, one or more relatively large flushing passages extending laterally through the neck, the outer open end of said passage or passages being positioned between regions where there is complete and continuous frictional contact between the neck and the barrel and a relatively 50 minute air passage or passages extending through the end wall of the bulb between the interior of the barrel and the interior of the bulb.

2. A syringe such as set forth in claim 1 in which the relatively large flushing channel or 55 channels extend laterally through the neck across the interior face of the end wall of the bulb.

3. A syringe such as set forth in claim 1 in which the relatively large flushing channel or 60 channels extend laterally through the neck across the interior face of the end wall of the bulb and in a direction to form an obtuse angle with respect to the longitudinal axis of the bulb and neck.

4. A syringe such as set forth in claim 1 in which the minute air passage or passages comprise a rigid tube or tubes extending through 65 the face of the end wall of the bulb into communication with the interior of the bulb.

5. A syringe such as set forth in claim 1 in which the minute air passage or passages comprise a rigid tube or tubes of corrosion-resistant 70

metal extending through the face of the end wall of the bulb into communication with the interior of the bulb.

6. A syringe such as set forth in claim 1 in which the minute air passage or passages comprise a rigid tube or tubes of corrosion-resistant metal extending through the face of the end wall of the bulb into communication with the interior of the bulb and terminate approximately flush with that face of the wall of a flushing channel which is closest to the interior of the barrel of the syringe. 80

7. A syringe such as set forth in claim 1 in which the relatively large flushing channel or 85 channels extend laterally through the neck across the interior face of the end wall of the bulb and in a direction to form an obtuse angle with respect to the longitudinal axis of the bulb and neck and in which at least one minute air passage extends through the face of the end wall 90 of the bulb into communication with the interior of the relatively large flushing channel or channels. 95

8. A syringe such as set forth in claim 1 in which the relatively large flushing channel or 100 channels extend laterally through the neck across the interior face of the end wall of the bulb and in a direction to form an obtuse angle with respect to the longitudinal axis of the bulb and neck and in which the minute air passage or 105 passages include a rigid tube extending through the face of the end wall of the bulb into communication with the interior of the bulb. 110

9. A syringe such as set forth in claim 1 in which the relatively large flushing channel or 115 channels extend laterally through the neck across the interior face of the end wall of the bulb and in a direction to form an obtuse angle with respect to the longitudinal axis of the bulb and neck and in which the minute air passage or 120 passages include a rigid tube extending through the face of the end wall of the bulb into communication with the interior of the bulb terminating approximately flush with that face of that wall of a flushing channel which is closest to the interior of the barrel of the syringe. 125

10. A syringe comprising a barrel provided at one end with a nozzle and at its opposite end with an inner surface adapted to frictionally engage the exterior of the neck and end walls of 130 a bulb, a compressible bulb having a neck and an end wall the end wall being thicker than the walls of the bulb and the neck, said thickened end wall and neck being adapted exteriorly thereof to frictionally engage said inner surface of 135 said barrel, the air content of the bulb being substantially less than the liquid-containing capacity of the barrel, one or more relatively large flushing passages extending laterally through the neck, the outer open end of said passage or passages being positioned between the regions where there is complete and continuous frictional contact between the neck and the barrel, relatively minute air passages extending through the thickened end wall of the bulb into the interior of the 140 bulb between the interior of the barrel and the interior of the bulb, the aggregate cross-sectional dimensions of all of the air passages through the said end wall of the bulb being so limited that upon inversion of the syringe, fluid contained in 145 the barrel will be restrained from passing into the bulb the thickened end wall of the bulb in the assembly of the bulb and barrel resisting reduction in size of the air passages less than the minimum requirements for proper expulsion of air 150

from the bulb through the air passages into the syringe barrel.

11. A syringe comprising a barrel provided at one end with a nozzle and at its opposite end 5 with an inner surface adapted to frictionally engage the neck of a bulb, a compressible bulb having an end wall and a neck adapted exteriorly thereof to frictionally engage said inner surface of said barrel and a relatively minute air 10 passage or passages extending through the end wall of the bulb between the interior of the barrel and the interior of the bulb; said minute air passage or passages comprising a rigid tube 15 through and surrounded by the compressible material of the end wall of the bulb and sufficiently rigid to resist reduction of the cross section of the passage or passages through the tube or tubes, upon compression of the compressible material of the neck of the bulb on insertion of the latter into the barrel, the cross sectional dimensions of the air passage or passages through the tube or tubes being so limited that upon inversion 20 of the syringe fluid contained in the barrel will be restrained from passing into the bulb.

OSCAR O. R. SCHWIDETZKY.
